Inventor:
Harold D. Forsyth,
By attorney, James J. Kelly.

UNITED STATES PATENT OFFICE

HAROLD D. FORSYTH, OF MARBLEHEAD, MASSACHUSETTS

DIE BLOCK

Application filed October 4, 1927. Serial No. 224,014.

This invention relates to die blocks such as are used on clicking machines for stamping out shoe uppers and the like, and the object is to provide a durable and inexpensive 5 construction for such blocks which will permit them to be firmly secured in place and also one adapted for use on existing machines without change of the latter.

My invention will be well understood by 10 reference to the following description taken in connection with the accompanying drawings of a single illustrative embodiment thereof, wherein:

Fig. 1 is a perspective view of a portion of 15 a clicking machine of known type with a die block embodying the invention in position on the bed thereof;

Fig. 2 is a plan view of the die block with 20 part broken away; and

Fig. 3 is a fragmentary vertical section on a larger scale showing one of the securing means.

In Fig. 1 I have shown as an illustration of 25 one type of machine on which the die block embodying my invention may be used a clicking machine having a reciprocating die-carrying head 5 adapted to stamp out work from leather or other sheet material which rests on the die block 7 supported on the bed 9 of the 30 machine. To clamp the block securely in position it may be secured by the hooked end or bill 11 (Fig. 3) of a bolt 13 carried adjacent one corner of the bed for securing one end of the block and a similar bolt 13^a located 35 adjacent the opposite corner of the bed. The type of machine shown is supplied with these bolts and also with similar bolts 15 along the front edge of the bed.

The die block 7, as best seen from Fig. 2, is 40 built up from suitable blocks of wood disposed with the end of the grain presented at the working faces of the block. For clearness the grain is indicated only at the broken away portion of Fig. 2. In the manufacture of 45 such a block suitable pieces of wood are selected and assembled to form one of the sections 17 of a length corresponding to the width or depth of the completed die block and a suitable number of such sections are arranged side by side to provide the desired

length, as illustrated in Fig. 2. The individual blocks and the sections are glued together in the customary manner.

Mechanical means are provided for holding 55 together the various sections of the block which may also provide for clamping it down on the bed of the machine. For this purpose I use suitable ties 19 which preferably are symmetrically arranged. In the present instance one is disposed midway of the depth 60 or width of the block and one adjacent each longitudinal edge. They are also located midway between the faces. In order to provide at the end of the tie a hollow or tubular 65 end with which the bill of a clamping hook may engage I may utilize for these ties a steel tube or pipe, as clearly shown in Fig. 3, and the ends of these tubes may be threaded to receive clamping nuts 21 cooperating with 70 washers 23 to provide a firm clamping together of the sections of the block in the longitudinal direction, viewing Fig. 2. The nut and washer is preferably recessed into the 75 end of the block, as indicated in Fig. 3, suitable clearance being provided to provide for the application of a socket wrench. The ends of the tubes being exposed at the ends of the blocks, the bills 11 of clamping hooks 13, or 13^a as the case may be, may enter the same and thus not only is a clamping together of 80 the sections provided for but an anchoring means for holding the block down upon the bed of the machine. To permit the utilization of the hook bolts 15 along the front edge of the bed thimbles 25 may be inserted in proper 85 position along the longitudinal edges of the block and midway of its thickness.

In the construction of die block described 90 the various sections of which it is made up are firmly tied and pressed together and the ties, consisting of the tube 19 and cooperating nuts 21, in themselves provide a simple and convenient means for receiving the bills of the clamping bolts. As the anchoring means 95 with which these bolts engage are built into the body of the block, there is no movement thereof relative to the block possible and an ample pressure may always be secured by means of these bolts firmly to clamp the block 100 against the bed of the machine. It is obvious

that this pressure acting on the tube is transmitted over a wide area of the block. The die block as shown may be turned upside down or end for end to equalize wear in the customary manner and may be resurfaced as usual. The arrangement and disposition of the ties 19 are such that there is no danger of their harming the resurfacing tools and any handling of the block is very simple since it is merely necessary to release the clamping bolts.

The inexpensive character of the construction shown is obvious.

Having described in detail the particular embodiment of my invention shown by way of example in the accompanying drawings, what I claim as new and desire to secure by Letters Patent I shall express in detail in the following claims.

20 Claims:

1. A die block for clicking machines or the like comprising a plurality of sections, symmetrically arranged tubes extending through said sections, clamping nuts threaded on the tubes, the ends of the tubes being exposed at the sides of the block to receive clamping hooks.

2. A die block for clicking machines or the like comprising a plurality of sections, ties 30 extending through the block and binding said sections together, said ties having tubular extremities exposed at the sides of the block to receive the bills of clamping hooks.

3. A die block for clicking machines or the like comprising a plurality of sections, symmetrically arranged tubes extending through said sections, clamping nuts threaded on the tubes and recessed into the sides of the block, the end of the tubes being exposed substantially flush with the ends of the block to receive the ends of clamping hooks.

In testimony whereof, I have signed my name to this specification.

HAROLD D. FORSYTH.
